UNITED STATES PATENT OFFICE.

ROBERT M. JONES, OF DENVER, COLORADO.

MACHINE FOR FORMING POLES, PILES, AND PIPES OF PLASTIC MATERIAL.

1,064,741.

Specification of Letters Patent. Patented June 17, 1913.

Application filed July 16, 1912. Serial No. 709,808.

To all whom it may concern:

Be it known that I, ROBERT M. JONES, a citizen of the United States, residing at Denver, in the county of Denver and State of Colorado, have invented certain new and useful Improvements in Machines for Forming Poles, Piles, and Pipes of Plastic Material, of which the following is a specification.

10 My invention relates to machines for constructing poles, piles, pipes and other similar articles, of concrete or other plastic material, and more particularly to machines adapted for use in the practice of the process 15 described in my application for patent, Serial No. 609,170, filed February 17, 1911.

The object of the present invention resides in the provision of a mechanism of simple construction by which a mass of concrete may be readily formed into an article of either tapering or cylindrical shape, preferably around a mandrel which after the plastic material has hardened, is removed. 20 I attain this object by the mechanism illustrated in the accompanying drawings in the various views of which like parts are similarly designated, and, in which,

Figure 1 represents an end elevation of the machine with the foundation upon which 30 it is supported shown in section, Fig. 2, a plan view of the machine drawn to a reduced scale, and Fig. 3, a side elevation of the same.

The machine is preferably installed upon 35 a foundation 19 composed of stone, concrete or other suitable material and provided with parallel trenches 14 for the admission of the weighted ends of a blanket 2 which forms part of the construction, as will hereinafter 40 be described.

The operating parts of the machine are mounted upon a base composed of two sections A and B which are supported upon the foundation beyond the opposite ends of the

45 two trenches 14. Each base section consists of two pairs of parallel I-beams 9 and 13, one of which is placed transversely upon the other and secured thereto by bolts or rivets. Mounted upon the upper pairs of 50 beams of the two base sections are double bearings 6 for the support of two rollers 4 which in the operation provide a rolling support for the body of plastic material while it is being shaped into the desired form.

55 The bearings 6 are fastened upon the base sections by means of stud bolts 16 and they

may be raised or lowered for the purpose of adjusting the position of the rollers, by means of wedge-shaped liners 17 which are interposed between the bearings and the upper surfaces of the beams.

60 Articulately connected with the base sections by means of knuckles 11 and 10 are two pairs of rocker arms 8 which at their upper extremities carry bearings 20 for the support 65 of two rollers 3, which by means of cranks 1 applied to their shafts are in the operation of the machine rotated in the same direction. The rollers 3 are yieldingly held in their normal position at substantially equal 70 distances from a vertical plane extending intermediate of the rollers 4, by means of pneumatic springs which are provided by oscillating cylinders 7 which are connected at opposite sides of the standards of the 75 bearings 6, and pistons 24 which are movably fitted in the said cylinders and pivotally connected with the respective rocker arms by means of sleeves 18. The cylinders 7 are by means of pipes 22 connected at 80 their opposite ends with a three way valve 25 adapted to place either end of the cylinders in communication with a source of air under compression. During the operation 85 of the machine, the air pressing upon the outer surfaces of the two pistons 24, provides the pneumatic springs which by opposing the outward movement of the rollers 3, exert a pressure upon the body of plastic material placed between them, and by introducing the air into the cylinders at the inner 90 sides of the pistons, the latter are moved outwardly to separate the rollers 3 for the purpose of removing the finished product, as will hereinafter be more fully described. 95 Stops 5 are secured to the bearings 6 to limit the outward movement of the rocker arms, the extreme positions of which have 100 been shown in broken lines in Fig. 1 of the drawings.

100 Loosely supported upon the rollers 3 is the blanket 2, the end portions of which hang over the outer sides of the same and are provided at their lower edges with weights 15 which in the operation, serve to 105 impart the required tension to the blanket.

In the construction shown in the drawings, the several rollers 4 and 3 are of tapering form and their longitudinal axes converge toward a point in the vertical plane 110 extending intermediate of the rollers of the two pairs. As a result of this arrangement,

and construction, a body of plastic material disposed upon the blanket between the rollers 3 will when the said rollers are rotated, assume a form which tapers in accordance 5 with the angle of convergence of the same and it will be understood without further illustration that to form an article of cylindrical shape, the various rollers comprised in the machine must be made cylindrical and 10 arranged in parallel relation to each other.

A platform 21 shown in Figs. 1 and 2 of the drawings, is provided to support the material before it is fed onto the blanket, as well as the finished product after it is discharged 15 from the same, and it will be understood that while two cranks have been shown as the simplest medium for imparting motion to the rollers 3, other means may be employed in case it is desired to operate the 20 machine by power.

Having thus described the mechanical construction of the machine, its operation will be readily understood. The plastic material of which the article is to be composed is 25 together with a suitable mandrel 23 to which, if so desired, the reinforcements to be embedded in the product, may be fastened, is placed in the sag of the belt between the rollers 3 and upon the rollers 4 after which 30 the rollers 3 are rotated in the same direction. The consequent longitudinal movement of the blanket and the pressure exerted by the air-cushions in the cylinders 7 upon the body of plastic material through the 35 medium of the rollers 3 will cause the said body to assume a conoidal shape around the mandrel. After one end of the belt has been lowered into the corresponding trench 14 of the foundation 9, as far as is advisable, the 40 rollers are rotated in the opposite direction and the movement of the blanket is in consequence reversed and the body of plastic material is thus together with the mandrel, rolled back and forth between the rollers 3 45 and upon the rollers 4 until it has acquired the desired form. To discharge the product from the machine compressed air is introduced through the pipes 22 into the inner ends of the cylinders 7 to cause by pressure 50 upon the respective pistons, the two rollers 3 to separate until the portion of the belt upon which the finished product is supported, extends level with the upper surfaces

of the rollers, when the product is moved onto the platform 21 where it remains until 55 it has hardened, after which the mandrel around which it is formed is removed.

It will be understood that to successfully operate the machine, it is necessary that the distance between the rollers 3 is at any point 60 less than the diameter at the corresponding point of the pole, pile or pipe formed between them.

Having thus described my invention what I claim and desire to secure by Letters 65 Patent is:

1. A machine of the class described comprising a pair of rotary rollers placed in spaced relation to each other, a blanket loosely supported thereon, and a support for 70 the sag of said blanket between said rollers.

2. A machine of the class described comprising a pair of rotary rollers placed in spaced relation to each other, a blanket loosely supported thereon, and a rolling support for the sag of said blanket between said 75 rollers.

3. A machine of the class described comprising a pair of rotary rollers laterally, movably mounted in spaced relation to each other, a blanket loosely supported thereon, and means to yieldingly oppose a lateral movement of said rollers.

4. A machine of the class described comprising a pair of rotary rollers laterally 85 movably mounted in spaced relation to each other, a blanket loosely supported thereon, and means normally, yieldingly opposing a lateral movement of said rollers and adapted to separate the same to increase the distance 90 between them, by moving them simultaneously in opposite directions.

5. A machine of the class described comprising a pair of rollers in spaced relation to each other, oscillatory bearings in which 95 said rollers are rotatably mounted, a blanket loosely supported on said rollers, and means to yieldingly oppose a movement of said bearings about their axes of oscillation.

In testimony whereof I have affixed my 100 signature in presence of two witnesses.

ROBERT M. JONES.
